UNITED STATES PATENT OFFICE

EDWARD ALLEN PIERCE, OF PORTLAND, OREGON

DENTIST'S EMERGENCY UNIT

Application filed July 22, 1930. Serial No. 469,692.

My invention is intended primarily for the use of the medical profession and more particularly for the use of dentists wherein the essential elements for the use of the 5 dental or medical man may be placed therein for emergency use.

The device consists of a box preferably made of non-corrosive material having a lid hingedly secured to the body of the box and 10 having means for maintaining the lid in a locked position. A plurality of compartments are disposed within the device in which the essential medical elements may be placed and a removable tray is disposed 15 within the box that is normally maintained in spaced relationship with the bottom of the box into which the instruments may be placed. The box and its entire contents may be maintained in a sterile condition by medicated agencies or through the application 20 of heat so that the same, when taken by the medical or dental practitioner, may be in a sterile condition when taken and in which condition the same may be maintained and 25 used and after use the entire contents and the box itself may be resterilized for further and future use.

The object of my invention is to provide the medical or dental practitioner with an 30 emergency unit that may be maintained in a sterilized and usable condition at all times and in which the essential elements for emergency purposes may be kept and from which the same may be taken and used, as desired.

35 A further object of my invention consists in providing an emergency unit that is relatively small and in which the essential elements may be placed and which the practitioner may take upon emergency calls and 40 through the dispensing of the contents of which, practically any and all emergency cases may be handled.

A still further object of my invention consists in providing a box having a plurality of 45 compartments, each of which is adapted for receiving articles therein and for the maintaining of the same therein, in usable form, until used.

A still further object of my invention consists in providing a box having a plurality of

vertically disposed compartments into which bottles may be placed and maintained in a vertical position until used.

With these and incidental objects in view, the invention consists in certain novel features of construction and combination of parts, the essential elements of which are set forth in the appended claim, and a preferred form of embodiment of which is hereinafter shown with reference to the drawing which accompanies and forms a part of this specification.

In the drawing:

Fig. 1 is a perspective, front view of the assembled box, partially broken away at its 65 front wall to show the internal construction of the same, the lid being shown as in an opened condition.

Fig. 2 is a sectional, side view of the 70 assembled device.

Like reference characters refer to like parts throughout the several views.

I preferably form my box as having end walls 1 and 2, a front wall 3 and a rear wall 4. The bottom 5 of the box preferably extends beyond the walls to form an outwardly extending ledge entirely around the bottom of the same. A primary partition 6 extends from the end walls 1 and 2 and in spaced relationship with the rear wall 4. The bottom 7 of the partition terminates substantially below the top of the walls. A plurality of partitions 8 are disposed between the primary partition 6 and the rear wall 4. The object of the partitions is to 75 form a plurality of compartments 9, each of which is adapted to receive a bottle, or vial therein, and to maintain the same in a substantially vertical condition. A removable tray 10 is removably disposed within the box, the same being supported upon corner posts 11 that are placed within the oppositely disposed corners of the primary compartment composing the box and upon which the tray rests, upon its oppositely disposed corners. The bottom 12, of the tray, is disposed in spaced relationship with the bottom 5 to form a compartment into which 80

medical instruments and supplies may be placed. The closure 13 is hingedly secured 85

90

95

100

to the body of the device by any suitable hinging means 14. A spring snap fastener 15 is secured to the front wall of the box, the locking lug 16 of which is adapted to engage 5 within the slot 17 of the fastener plate and to maintain the lid closed against a reacting element. A plunger 18 outwardly extends through the front wall which is adapted for hand manipulation and to disengage the locking lug from the locking plate. It is highly 10 desirable that a fastener of this kind be used, as the emergency unit is truly intended as an emergency unit and the locking of the same might, in a degree, spoil the utility of 15 the same especially if it were key locked.

While the form of mechanism herein shown and described is admirably adapted 20 to fulfill the objects primarily stated, it is to be understood that it is not intended to confine the invention to the one form of embodiment herein shown and described, as it is susceptible of embodiment in various 25 forms, all coming within the scope of the claim which follows.

25 What I claim is:

A container of the class described, comprising a bottom, side walls, end walls and a lockable hinged closure therefor, a tray 30 formed with a bottom, side walls and end walls, arranged within the container and supported in spaced relation to the bottom thereof by reinforcing members within the container, a vertical wall arranged longitudinally of the container abutting one wall 35 of the tray and extending above the bottom thereof to prevent displacement of the tray with respect to the container, a plurality of partitions arranged in spaced relation longitudinally of the box and having their 40 edges on one side abut the side wall of the container and their opposite edges abutting the vertical wall.

EDWARD ALLEN PIERCE.
